LIGHTNING ARRESTER

Arthur A. Olsen, Pittsfield, Mass., assignor to
 General Electric Company, a corporation of
 New York

Application March 5, 1945, Serial No. 581,082

5 Claims. (Cl. 175—30)

1

My invention relates to lightning arresters such as are used for the protection of electric power transmission lines and associated apparatus from the effects of excessive voltages due to lightning, switching operations or other causes.

Lightning arresters generally consist of a gap structure connected in series with a current limiting element. The current limiting element should have the property of decreasing and increasing its resistance as the discharge current increases and decreases to such a degree that the voltage across the arrester during discharge is held to safe values for connected apparatus. The gap structure performs the function of a circuit breaker by interrupting the power follow current permitted to flow through the arrester by the current limiting element.

For high voltage distribution lightning arrester applications, the gap and current limiting elements are usually mounted in a heavy insulating tube with suitable end fittings and are thus completely sealed against the entrance of moisture. Where such lightning arresters are subjected to service conditions over and above that for which the arresters are designed, the gap or current limiting elements cannot cope with these conditions and arc-over occurs. A high pressure is thus built up within the heavy sealed insulating housing which may cause the arresters to fail with such violence that they shatter like bombs, thereby not only endangering personnel but at the same time damaging surrounding equipment.

It is an object of my invention to provide a new and improved lightning arrester in which shattering of the lightning arrester casing with damage to surrounding equipment or adjacent operating personnel will not occur.

It is another object of my invention to provide a pressure release diaphragm for a high voltage lightning arrester whereby blowing apart of the porcelain insulator housing the lightning arrester with resultant damage to adjacent equipment is prevented.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawing in which Fig. 1 is an elevational view, partly in section, of a lightning arrester embodying my invention; Fig. 2 is a view taken on line 2—2 of

2

Fig. 1, and Fig. 3 is an elevational view of another lightning arrester embodying my invention.

Referring now to the drawing I have illustrated a lightning arrester generally indicated at 1 in Fig. 1, which includes a casing having a cylindrical wall portion 2 formed of weatherproof insulating material, such as porcelain. The insulating casing 2 is closed at its upper end by means of an end plate 3 arranged in sealing engagement with the upper end of cylinder 2 by virtue of a gasket 4. A heavy metal end cap 5 fastened to the upper end of casing 2 by means of suitable cement 6 completely seals the upper end of the lightning arrester housing. A plurality of suitable clamping means 7 suitably welded to metal cap 5 provide means whereby end fittings or other arrester units may be fastened thereto.

The lower end of the insulating casing 2 is similarly closed by a heavy metal end cap 8 held in sealing engagement at the lower end of cylinder 2 by means of cement 9. End cap 8 is also provided with clamping means 10 to which may be fastened a suitable base member (not shown) or another similar lightning arrester unit as will become apparent by an examination of Fig. 3.

It will be obvious that the gap structure and current limiting element of the lightning arrester of my invention may take any suitable form, such for example as is disclosed in McEachron Patent 2,151,559, granted March 21, 1939, and assigned to the same assignee as the present application. As illustrated in the drawing, I provide a plurality of current limiting elements 11 alternately and serially arranged with a plurality of gap units 12. The current limiting elements 11 are all identical, the upper one in Fig. 1 being shown in section as comprising a disk 13 of a resistance material of the type having a high inverse voltage resistance characteristic. A suitable resistance material for this purpose is disclosed in United States Patent 1,822,742, McEachron, granted September 8, 1931, and assigned to the same assignee as the present application. The disk of resistance material 13 of each current limiting element is preferably provided with a ceramic insulating collar 14 pressed and fired as an inherent part of the disk 13, thereby assuring the maximum discharge capabilities of the disk.

Each series gap element 12, as may be observed from the uppermost gap unit in Fig. 1, consists of two electrodes 15 and 16, respectively, which are separated by insulating means generally indicated in Fig. 1 as a cylindrical spacer 17 formed of porcelain or the like. In order to control the voltage distribution across the gap element de-

fined by electrodes 15 and 16, I provide a horse-shoe-shaped member 18 of resistance material preferably of the same material as the disks 13. The open ends of the horseshoe-shaped member 18 are respectively connected to the electrodes 15 and 16 by means of conductors 19 and 20. A symmetrical field distribution is provided by virtue of the fact that the horseshoe-shaped resistor 18 surrounds the gap structure including electrodes 15 and 16.

As illustrated in the drawing, eight current-limiting elements 11 and eight gap elements 12 are arranged in series relationship with a gap structure interposed between two current limiting elements. This column defined by alternate elements 11 and 12, is supported by a suitable spacer member 21 in the form of a conducting cylinder, and the upper end of the lightning arrester column is held in conducting engagement with the end cap 5 by means of a compression spring 22, which furthermore maintains the lightning arrester column in position.

When the lightning arrester fails an arc strikes between end caps 5 and 8 within insulating cylinder 2. This arc causes hot gases and vapors to build up rapidly which may cause the insulating cylinder 2 to blow apart with tremendous violence. In accordance with my invention, I provide a pressure relief diaphragm 23 between lower end cap 8 and gasket 24 engaging the lower end of cylinder 2. This pressure relief diaphragm 23 is preferably formed of lead and provided with an annular ridge 25 so as to define an annular passageway 26 between diaphragm 23 and lower end plate 8. The metal end cap 8 is provided with a plurality of pressure relief openings 27 communicating with the annular passageway 26. In order to prevent the spacer 21 from cutting into the lead pressure relief diaphragm 23 I preferably provide a supporting member 28 which spreads the weight of the current limiting and gap elements over a larger area of diaphragm 23. It will be observed that the spacer 21 spaces the gap structure sufficiently from diaphragm 23 so that heat from arcing across the gap structure short of failure of the arrester will not adversely affect diaphragm 23.

The pressure relief diaphragm 23 provides the desired moisture seal while the perforated end cap 8 provides mechanical protection for the diaphragm and a rugged means for supporting the arrester and connecting it to adjacent units if desired. When an arc strikes between the end caps 5 and 8, it immediately burns through the diaphragm 23 and connects passageway 26 with the interior of cylinder 2 so that any appreciable pressure build-up is avoided by permitting the generated gases to escape through annular passageway 26 and pressure relief openings 27. Instead of the insulating cylinder 2 blowing apart with great violence the porcelain container 2 merely breaks apart for thermal reasons due to the great heat produced by the arc, with the pieces of the container harmlessly dropping to the ground.

My invention is particularly useful when a plurality of units such as 1 are mounted in end to end relationship such as shown in Fig. 3, as is often the case for higher voltage installations.

In view of the detailed description included above, the operation of the lightning arrester embodying my invention described above will be obvious to those skilled in the art and no further discussion will be included herein.

While I have shown and described a particular

embodiment of my invention, it will be obvious to those skilled in the art that various changes and modifications may be made without departing from my invention in its broader aspects and I, therefore, aim in the appended claims to cover all such changes and modifications as fall within the true spirit and scope of my invention.

What I claim as new and desire to secure by Letters Patent of the United States is:

10. 1. In a lightning arrester comprising an insulating casing, a gap structure in said casing, means including a conducting member for sealing one end of said casing, a diaphragm for sealing the other end of said casing, said gap structure being sufficiently displaced from said diaphragm that heat from said gap structure will not adversely affect said diaphragm, closure means including a conducting member for said other end of said casing for protecting said diaphragm, said diaphragm acting as a pressure relief device upon failure of said arrester by being burned through by the arc striking between said conducting members within said casing and which might otherwise cause said casing to shatter with great violence, and means comprising openings in said closure means for permitting gases passing through the hole burned in said diaphragm by the arc upon failure of said arrester to escape to atmosphere.
15. 2. In a lightning arrester comprising an insulating casing, a gap structure in said casing, means including a conducting member for sealing one end of said casing, a lead diaphragm for sealing the other end of said casing, said gap structure being sufficiently displaced from said lead diaphragm so that heat from said gap structure will not adversely affect said diaphragm, closure means including a conducting member for said other end of said casing for protecting said diaphragm, said diaphragm acting as a pressure relief device upon failure of said arrester by being burned through by the arc striking between said conducting members within said casing and which might otherwise cause said casing to shatter with great violence, and means comprising openings in said closure means for permitting gases passing through the hole burned in said diaphragm by the arc upon failure of said arrester to escape to atmosphere.
20. 3. In a lightning arrester comprising an insulating casing, a gap structure in said casing, means for sealing one end of said casing, a diaphragm for sealing the other end of said casing, said gap structure being sufficiently displaced from said diaphragm so that heat from said gap structure will not adversely affect said diaphragm, closure means including a conducting member for said other end of said casing for protecting said diaphragm, said diaphragm acting as a pressure relief device upon failure of said arrester by being burned through by the arc striking between said conducting members within said casing and which might otherwise cause said casing to shatter with great violence, and means comprising openings in said closure means for permitting gases passing through the hole burned in said diaphragm by the arc upon failure of said arrester to escape to atmosphere.
25. 4. In a lightning arrester comprising an insulating casing, a gap structure in said casing, means for sealing one end of said casing, a diaphragm for sealing the other end of said casing, said gap structure being sufficiently displaced from said diaphragm so that heat from said gap structure will not adversely affect said diaphragm, closure means including a conducting member for said other end of said casing for protecting said diaphragm, said diaphragm acting as a pressure relief device upon failure of said arrester by being burned through by the arc within said casing which might otherwise cause said casing to shatter with great violence, said diaphragm having an annular ridge so as to define with said closure member an annular passageway, and means comprising openings in said closure member leading to said passageway for permitting gases passing through the hole burned by the arc in said diaphragm upon failure of said arrester to escape to atmosphere.
30. 5. In an electrical device comprising an insulating casing, means including a conducting member for sealing one end of said casing, a diaphragm for sealing the other end of said casing, closure means including a conducting member for said other end of said casing for protect-
35. 6. In a lightning arrester comprising an insulating casing, a gap structure in said casing, means for sealing one end of said casing, a diaphragm for sealing the other end of said casing, said gap structure being sufficiently displaced from said diaphragm so that heat from said gap structure will not adversely affect said diaphragm, closure means including a conducting member for said other end of said casing for protecting said diaphragm, said diaphragm acting as a pressure relief device upon failure of said arrester by being burned through by the arc striking between said conducting members within said casing and which might otherwise cause said casing to shatter with great violence, and means comprising openings in said closure means for permitting gases passing through the hole burned in said diaphragm by the arc upon failure of said arrester to escape to atmosphere.
40. 7. In a lightning arrester comprising an insulating casing, a gap structure in said casing, means for sealing one end of said casing, a diaphragm for sealing the other end of said casing, said gap structure being sufficiently displaced from said diaphragm so that heat from said gap structure will not adversely affect said diaphragm, closure means including a conducting member for said other end of said casing for protecting said diaphragm, said diaphragm acting as a pressure relief device upon failure of said arrester by being burned through by the arc striking between said conducting members within said casing and which might otherwise cause said casing to shatter with great violence, and means comprising openings in said closure means for permitting gases passing through the hole burned in said diaphragm by the arc upon failure of said arrester to escape to atmosphere.
45. 8. In a lightning arrester comprising an insulating casing, a gap structure in said casing, means for sealing one end of said casing, a diaphragm for sealing the other end of said casing, said gap structure being sufficiently displaced from said diaphragm so that heat from said gap structure will not adversely affect said diaphragm, closure means including a conducting member for said other end of said casing for protecting said diaphragm, said diaphragm acting as a pressure relief device upon failure of said arrester by being burned through by the arc striking between said conducting members within said casing and which might otherwise cause said casing to shatter with great violence, and means comprising openings in said closure means for permitting gases passing through the hole burned in said diaphragm by the arc upon failure of said arrester to escape to atmosphere.
50. 9. In a lightning arrester comprising an insulating casing, a gap structure in said casing, means for sealing one end of said casing, a diaphragm for sealing the other end of said casing, said gap structure being sufficiently displaced from said diaphragm so that heat from said gap structure will not adversely affect said diaphragm, closure means including a conducting member for said other end of said casing for protecting said diaphragm, said diaphragm acting as a pressure relief device upon failure of said arrester by being burned through by the arc striking between said conducting members within said casing and which might otherwise cause said casing to shatter with great violence, and means comprising openings in said closure means for permitting gases passing through the hole burned in said diaphragm by the arc upon failure of said arrester to escape to atmosphere.
55. 10. 3. In a lightning arrester comprising an insulating casing, a gap structure in said casing, means for sealing one end of said casing, a diaphragm for sealing the other end of said casing, said gap structure being sufficiently displaced from said diaphragm so that heat from said gap structure will not adversely affect said diaphragm, closure means including a conducting member for said other end of said casing for protecting said diaphragm, said diaphragm acting as a pressure relief device upon failure of said arrester by being burned through by the arc striking between said conducting members within said casing and which might otherwise cause said casing to shatter with great violence, and means comprising openings in said closure means for permitting gases passing through the hole burned in said diaphragm by the arc upon failure of said arrester to escape to atmosphere.
60. 11. 4. In a lightning arrester comprising an insulating casing, a gap structure in said casing, means for sealing one end of said casing, a diaphragm for sealing the other end of said casing, said gap structure being sufficiently displaced from said diaphragm so that heat from said gap structure will not adversely affect said diaphragm, closure means including a conducting member for said other end of said casing for protecting said diaphragm, said diaphragm acting as a pressure relief device upon failure of said arrester by being burned through by the arc striking between said conducting members within said casing and which might otherwise cause said casing to shatter with great violence, and means comprising openings in said closure means for permitting gases passing through the hole burned in said diaphragm by the arc upon failure of said arrester to escape to atmosphere.
65. 12. 5. In a lightning arrester comprising an insulating casing, a gap structure in said casing, means for sealing one end of said casing, a diaphragm for sealing the other end of said casing, said gap structure being sufficiently displaced from said diaphragm so that heat from said gap structure will not adversely affect said diaphragm, closure means including a conducting member for said other end of said casing for protecting said diaphragm, said diaphragm acting as a pressure relief device upon failure of said arrester by being burned through by the arc striking between said conducting members within said casing and which might otherwise cause said casing to shatter with great violence, and means comprising openings in said closure means for permitting gases passing through the hole burned in said diaphragm by the arc upon failure of said arrester to escape to atmosphere.
70. 13. 6. In a lightning arrester comprising an insulating casing, a gap structure in said casing, means for sealing one end of said casing, a diaphragm for sealing the other end of said casing, said gap structure being sufficiently displaced from said diaphragm so that heat from said gap structure will not adversely affect said diaphragm, closure means including a conducting member for said other end of said casing for protecting said diaphragm, said diaphragm acting as a pressure relief device upon failure of said arrester by being burned through by the arc striking between said conducting members within said casing and which might otherwise cause said casing to shatter with great violence, and means comprising openings in said closure means for permitting gases passing through the hole burned in said diaphragm by the arc upon failure of said arrester to escape to atmosphere.
75. 14. 7. In a lightning arrester comprising an insulating casing, a gap structure in said casing, means for sealing one end of said casing, a diaphragm for sealing the other end of said casing, said gap structure being sufficiently displaced from said diaphragm so that heat from said gap structure will not adversely affect said diaphragm, closure means including a conducting member for said other end of said casing for protecting said diaphragm, said diaphragm acting as a pressure relief device upon failure of said arrester by being burned through by the arc striking between said conducting members within said casing and which might otherwise cause said casing to shatter with great violence, and means comprising openings in said closure means for permitting gases passing through the hole burned in said diaphragm by the arc upon failure of said arrester to escape to atmosphere.

ing said diaphragm, said diaphragm acting as a pressure relief device upon failure of said electrical device with consequent arcing in said casing between said conducting members by being burned through by the arc within said casing which might otherwise cause high pressure to be developed in said casing causing said casing to shatter with great violence, and means comprising openings in said closure means for permitting gases passing through the hole burned in said diaphragm by the arc upon failure of said electrical device to escape to atmosphere.

5. In a lightning arrester comprising an insulating casing, a gap structure in said casing, means for sealing one end of said casing, a diaphragm for sealing the other end of said casing, means for positioning said gap structure a sufficient distance from said diaphragm so that heat from said gap structure will not adversely affect said diaphragm, a closure member for said other end of said casing for protecting said diaphragm, said diaphragm acting as a pressure relief device

upon failure of said arrester by being burned through by the arc within said casing which might otherwise cause said casing to shatter with great violence, said diaphragm having an annular ridge arranged between said casing wall and said means for positioning said gap structure so as to define with said closure member an annular passageway, and means comprising openings in said closure member leading to said passageway for permitting gases passing through the hole burned in said diaphragm by the arc upon failure of said arrester to escape to atmosphere.
